UNITED STATES PATENT OFFICE

2,580,850

COMPOUND MASTER CYLINDER

Alfred B. Seppmann, Mankato, Minn.

Application August 17, 1946, Serial No. 691,251

2 Claims. (Cl. 60—54.6)

1

This invention relates to fluid pressure braking systems such as employed in automobiles.

Particularly, the invention has reference to a compound master cylinder for producing a two-phase operating function.

The purpose of the two-phase feature is to rapidly take up slack in the brakes in the initial portion of the operation of the piston, by means of low pressure high-speed movement of fluid, and on the final portion of the operation of the piston to apply high pressure movement of the fluid.

Such master cylinders usually utilize two pistons of different diameter, arranged so that in the initial phase of the braking operation, the larger diameter piston applies force. In the second phase of the operation, a relief valve comes into play relieving the pressure on the fluid in the cylinder having the larger diameter piston, whereby the smaller diameter piston is utilized for applying high pressure at a slower speed.

An object of the present invention is the provision of a new arrangement of pistons in such a compound master cylinder, whereby the larger diameter piston telescopes over the smaller diameter piston.

Another object of the invention resides in the feature that the smaller diameter piston is fixed to a cap which closes the cylinder and remains stationary, and the larger diameter piston is reciprocable in the cylinder and telescopes over the smaller diameter piston. An advantage resulting from this design is ease in assembling and disassembling the parts, and the elimination of constructional parts for closing the cylinder.

An important advantage in the present invention resides in a new and improved relief valve for relieving the pressure on the fluid in the cylinder having the larger diameter piston at the beginning of the second phase of operation. The device includes a reservoir in communication with the large operating cylinder proper, and when the relief valve is opened fluid from the cylinder proper passes into the reservoir.

Another important feature of the invention is that the relief valve is arranged to permit reverse flow of fluid from the reservoir into the large operating cylinder, to enable the larger diameter piston to build up additional pressure by means of sudden and successive reciprocations in the braking operation.

Another advantage of the invention resides in the arrangement of ports and passages in the relief valve so that when fluid escapes there-through it is shielded from passing outwardly

of the reservoir through vents which are usually provided in such cylinders.

Another advantage of the invention is the provision of a brass sleeve lining in the cylinder

5 housing, in which the larger diameter piston operates. In hydraulic systems there is usually a small quantity of moisture in the fluid which tends to accumulate in and rust the interior of the cylinder. The provision of such a brass sleeve lining prevents rust from forming as a result of such moisture.

Another object of the invention resides in the cylinder for reciprocation of the piston and the fluid reservoir being formed integral, resulting 10 in an economical structure.

A further object of the invention is the provision of a new and improved means for mounting a stop-light actuating switch on the master cylinder.

15 With these and other objects in view, my invention consists in the construction, arrangement and combination of the various parts of my device whereby the objects contemplated are attained, as hereinafter more fully set forth, 20 pointed out in the claims and illustrated in the accompanying drawings, wherein:

Fig. 1 is a semi-diagrammatic view of a hydraulic braking system, including the master cylinder of my invention, showing the master cylinder in exaggerated size;

Fig. 2 is a top view of the master cylinder;

Fig. 3 is an end view, as viewed from the left of Fig. 2;

Fig. 4 is a longitudinal sectional view, on an enlarged scale, taken on line 4—4 of Fig. 2;

Fig. 5 is a view similar to Fig. 4, showing the reciprocable piston in extended position;

Fig. 6 is a vertical cross-section taken on line 6—6 of Fig. 5;

Fig. 7 is an enlarged vertical sectional view of the relief valve;

Fig. 8 is a horizontal sectional view taken on line 8—8 of Fig. 7; and

Fig. 9 is a sectional view of the retarding valve 45 showing its position during back flow of fluid from the brakes to the master cylinder.

Referring in detail to the drawings, Fig. 1 shows a diagrammatic arrangement of a braking system, and the compound master cylinder is 50 indicated at 12, and a brake pedal 14 for operating the cylinder. Connected to the outlet 16 of the cylinder are conduits 18 leading to fluid motors 20. Actuation of the fluid motors expands the brake shoes 22 into engagement with 55 brake drums 24 in a well-known manner.

The master cylinder is formed as a unitary casting having a fluid reservoir 26 and a large operating cylinder 28. For purposes of identification the left end of the cylinder (Fig. 4) will be referred to as the rear end, and the right end the front end. At the rear end of the operating cylinder is a flange 30 for securing the master cylinder to a suitable mounting on the automobile. Outwardly of the flange 30 is a smaller flange or rib 32 over which may be secured a flexible covering for enclosing that end of the cylinder against the entrance of foreign matter. Both ends of the operating cylinder 28 are open in the formation of the article. The rear end of the cylinder has a reduced portion 34 and forward of the reduced portion 34 is an enlarged portion 36 extending to the front end thereof. A shoulder 35 is thus formed at the rear end of the enlarged portion 36. The open front end is closed by a cap 38 having threaded securing in that end of the cylinder. The cap 38 is provided with a central threaded bore 40, and a central cavity 41 in its inner face.

The enlarged portion 36 of the operating cylinder 28 is provided with a movable brass sleeve 42.

A stationary piston 44 having a flange 46 is secured in the operating cylinder 28 with the flange 46 positioned adjacent the inner end of cap 38, and the piston extends axially into the operating cylinder 28. Sealing means 48 is positioned on each side of the flange 46, and the piston is retained in position by turning the cap 38 tight in the cylinder, and securing the flange 46 of the piston 44 between the cap and the adjacent end of the sleeve 42, and the other end of the sleeve abuts against the shoulder 35 and is held in position thereby, and the piston 44 is thereby held in position. The rear end of the piston 44 is provided with a flange 50 having a plurality of axial openings 52 spaced therearound. Rearward of the flange 50 is a reduced extension 54 having an annular recess 56 adjacent the rear face of the flange 50. Cup-shaped sealing means 58 is provided with a central opening for fitting in the annular recess 56. The sealing means 58 is adapted to seat against the rear face of the flange 50 and seal the openings 52. A central bore 59 is formed in the piston 44, opening into the cavity 41 in the end cap 38 at one end, and opening at the other end into the interior of a secondary cylinder, hereinafter described.

Operation of the master cylinder is effected by a reciprocable piston 60, in the operating cylinder 28. The piston 60 is provided at its rear end with a cavity 62 for the reception of a rod 64 secured to the brake pedal 14. The front end of the piston 60 is hollowed, forming a secondary cylinder 66.

Surrounding the exterior of the piston 60, intermediate the ends thereof, is a flange 68 having an annular recess 70 formed therein. A cup-shaped sealing means 72 is fitted in the recess 70 and adapted to have sealing engagement directly with the brass sleeve lining 42 in the operating cylinder 28. Adjacent the rear end of the piston 60 is an annular recess 74, in which is positioned another cup-shaped sealing means 76 having sealing engagement with the reduced portion 34 of the operating cylinder.

A compression spring 78 is placed in the secondary cylinder 66 formed in the piston 60. This compression spring is biased between the inner end of the cylinder 66 and the rear end of the piston 44, and biases the reciprocable piston 60

to the left as shown in Fig. 4, or to its retracted position. Surrounding the reciprocable piston 60 is another compression spring 79, which is biased between the flange 68 on the reciprocable piston, and the flange 46 on the stationary piston 44. This spring also urges the reciprocable piston to retracted position. A plurality of openings 80 are formed in the reciprocable piston 60 at spaced intervals therearound, and are so positioned that when the piston 60 is in its retracted position as shown in Fig. 4, they communicate between the interior of the piston 60 and the operating cylinder 28.

Positioned in the cavity 41 in the inner face of the cap 38 is a retarding valve indicated in its entirety by the numeral 81. The retarding valve 81 includes a metal cup 82 having a flange 84 around its marginal edge. A compression spring 86 is biased between the flange 84 and the outer end of the piston 44. The cup 82 is provided with a plurality of openings 88 in its end surface. A flexible disc 90, such as rubber or leather, is secured to the inner surface of the cup 82 by means of a rivet 92, and is adapted to overlap and close the openings 88. A second disc 94 is positioned between the flange 84 of the cup 82 and the shoulder constituting the bottom of the cavity 41 of the cap 38. This disc 94 is provided with a central opening 96.

Threaded into the central bore 40 of the cap 38 is a plug 98. The plug 98 has a central bore 100 therethrough, in alignment with the opening 96, and terminating forwardly in an enlarged bore 102 for connection to the outlet 16 of the master cylinder which leads to the fluid braking system. Formed toward the front of the plug 98 is an enlarged shoulder 104, and outwardly of the shoulder 104 is a further enlarged head in the nature of a nut as indicated at 106. A stop-light switch, indicated generally at 108, is provided with a ring 110 surrounding the plug 98 and bearing on the shoulder 104. This ring forms an annular recess 112 around the reduced portion of the plug 98. Sealing means 114 is interposed between the ring 110 and the front surface of the cap 38, and between the ring 110 and the head 106. By tightening the plug in the opening 40 of the cap, the ring 110 and the stop-light switch are secured tightly in position. A bore 116 communicates between the central bore 100 of the plug and the annular recess 112. A similar bore 118 is formed radially through the ring 110 and communicates between the annular recess 112 and the interior of the stop-light switch 108.

Formed in the wall between the reservoir 26 and the large operating cylinder 28 is a large port 120 positioned adjacent the shoulder 35. A short distance rearwardly of the port 120 is a smaller port 122 in the same wall. Toward the rear of the reservoir is an enlarged threaded opening 124 communicating with the interior of the operating cylinder 28 for the insertion of a relief valve mechanism 126. The brass sleeve lining 42 is formed with appropriate openings to register with ports and openings 120, 122 and 124. The valve 126 includes a chambered body 128 having a reduced lower end 130 for threading into the opening 124. A port 132 is formed centrally in the reduced portion 130 and communicates between the operating cylinder 28 and the interior of the chambered body 128. Surrounding the port 132 on the interior surface of the chambered body is a raised shoulder 134. Formed in the side wall of the chambered body 128 above the raised shoulder 134 are a plurality

of radial ports 136 communicating between the interior of the chambered body and the reservoir 26.

A valve closure member 138 is positioned in the chambered body 128 and provided on its bottom with a resilient sealing means 140 for engagement with the upper surface of the raised shoulder 134 for sealing the port 132. The chambered body 128 is formed with its top open, which is closed by a plug 142 threaded in an enlarged portion in the upper end of the chambered body. At the bottom of such enlarged portion are a plurality of radial ports 144 communicating between the interior of the chambered body, above the valve member 138, and the reservoir. The lower surface of the threaded plug 142 may be provided with openings 146 so spaced around its periphery that in any position of the plug 142 at least some of the ports 144 will be open and free for the passage of fluid therethrough. Biased between the plug 142 and the valve closure member 138 is a compression spring 148.

Through the bottom of the chambered body 128 are a plurality of passages 150 extending radially into the chambered body, and then downwardly and opening at the lower surface of the reduced portion 130 of the relief valve. These passages 150 communicate between the reservoir 26 and the operating cylinder 28, and by-pass the interior of the chambered body 128.

The lower surface of the reduced portion of the relief valve is concave in formation, and is provided with a downwardly extending projection 152 having an annular recess 154 positioned adjacent the concave lower surface. A flexible disc 156, such as rubber or leather, having a central opening is placed in the annular recess 154 and lies against the concave lower surface of the relief valve to normally close the ports formed by the passages 150.

Above the relief valve 126 is a threaded opening 158 for the insertion of the relief valve. This opening 158 is closed by a plug 160. The plug 160 is hollowed-out as shown at 162 and at the top of the hollowed portion 162 is one or more horizontal vents 164. The lower end of the hollowed portion 162 is substantially closed by a disc 166 having a central opening. The disc 166 thus prevents oil from passing out through the vent 164, such as might occur upon sudden return movement of the large piston 60, in its cylinder, while at all times insuring proper opening for the passage of atmosphere.

An opening 168 is formed in the top surface of the reservoir over the ports 120 and 122, to provide access for forming the ports 120 and 122, and is closed by a snap metal disc 170.

Operation

Figure 4 shows the reciprocable piston 60 in retracted position. On the initial forward movement of the piston 60, it is moved to the right by the brake pedal. The port 122 is sealed-off by the sealing means 12, and the ports 80 are sealed off by the sealing means 58. The spring 148 has sufficient compression to normally retain the relief valve 126 closed, and fluid in the operating cylinder 28 builds up in pressure and passes through the ports 52 into the interior of the reciprocable piston 60, and is forced through the bore in the stationary piston 44 into the cavity 41 in the cap 38. Pressure built up here actuates the flexible disc 90, of the retarding valve assembly and opens the ports 88

in the retarding valve 81, permitting the fluid to pass on into the braking system (see Fig. 5). The effect of this initial movement is to produce low pressure by the reciprocable piston 60 at a rate determined by the reduction in volume of the operating cylinder 28, ahead of the piston 60.

After the slack has been taken out of the braking system and the brake shoes are in engagement with the brake drums, back pressure is developed in the forward portion of the cylinder 28, to overcome the compression in the spring 148 in the relief valve 126. At this point, the valve closure member 138 is raised, relieving the pressure built up in the operating cylinder 28.

The passage of fluid through the port 132 in the relief valve 126 raises the valve closure member 138 above the radial ports 136 and permits fluid to pass into the reservoir, as indicated in Fig. 5.

By the reduction of pressure in the operating cylinder 28 the fluid ceases to flow through the ports 52 in the stationary piston 44 and the result of further movement of the reciprocable piston 60 causes the fluid in the interior of the piston 60 to be forced into the braking system. By this action, the speed of the flow of fluid into the braking system is reduced, but the pressure exerted thereon is greatly increased and thus provided adequate, rapid, final braking action.

To build up greater pressure in the operating cylinder 28 the brake pedal may be actuated two or three times in quick succession. As the piston 60 moves quickly to retracted position, the spring 86 in the retarding valve 81 retains the retarding valve closed, preventing backflow of fluid from the braking system. It is only after a slight lapse of time that the fluid from the braking system reverses through the retarding valve 81 and will not reverse when the piston 60 is reciprocated quickly.

Also, as the piston 60 retracts, the flexible disc 156 on the relief valve permits fluid from the reservoir to pass through the passages 150 into the operating cylinder 28. This additional quantity of fluid in the operating cylinder 28 enables increased pressure to be exerted. The plurality of passages 150 in the relief valve 126 permits sudden flow of fluid from the reservoir 26 into the operating cylinder 28, when the piston 60 moves to retracted position, which causes a partial vacuum in the operating cylinder and opening of the valve 152. This action is particularly effective when the brake pedal is actuated several times quickly.

After pressure is released from the brake pedal, the back pressure of fluid from the braking system opens the retarding valve 81, as shown in Fig. 9, and flows into the interior of the master cylinder again. When the piston 60 moves to retracted position the ports 80 are again in communication between the interior of the piston 60 and the operating cylinder 28, and the fluid on backflow from the brakes passes therethrough into the cylinder 28.

The radial ports 144 above the valve closure member 138 provide vent means above the valve closure member 138 to permit raising of the valve closure member.

The horizontal disposition of the ports 136 assures that any fluid passing therethrough travels horizontally and prevents loss of fluid out of the reservoir, as would occur if these vents were placed vertically, as they are in most old type devices.

The stop-light switch 108 may be rotated to any position around the plug 98, and in all positions thereof, the bore 118 is in communication with the annular recess 112.

The reduced area of the upraised shoulder 134, and the resilient sealing means 140 on the valve closure member 138, insures that tight sealing engagement will be effected for closing the central bore 132. Grit or sand will not prevent tight sealing of this bore, as it would in the case of metal-to-metal contact.

While I have herein shown a particular embodiment of my invention, it will be understood of course that I do not wish to be limited thereto since many modifications may be made, and I therefore contemplate by the claims appended hereto to cover any such modifications or substitutions of equivalents as fall within the true spirit and scope of my invention.

I claim:

1. In a compound master cylinder for a braking system, a fluid reservoir, a cylinder, a hollow piston reciprocable in the cylinder and having a retracted position at one end of the cylinder, a stationary piston secured in the other end of said cylinder and co-axially aligned with the hollow piston, the hollow piston being adapted to telescope over the stationary piston, the hollow piston having formed therein openings communicating between the interior of the hollow piston and the cylinder when the hollow piston is in retracted position, said openings in the hollow piston being closed when the hollow piston is extended, the stationary piston having a cupped sealing means cooperating with the interior of the hollow piston, said stationary piston having openings therethrough adjacent the periphery of said cupped sealing means permitting flow of fluid from the cylinder into the interior of the hollow piston past the peripheral flange of said sealing means, there being an opening communicating between the cylinder and reservoir, and spring biased valve means normally closing said last opening and responsive to predetermined pressure in said last mentioned cylinder to open communication between it and the reservoir, said stationary piston having a bore communicating between the interior of the hollow piston and the braking system and a retarding valve between said bore and the braking system.

2. In a compound master cylinder for a braking system, a reservoir, a cylinder communicating with said reservoir, said cylinder being formed open at both ends and having a shoulder in one of said ends, a cap closing said last mentioned end of said cylinder, a stationary piston having a flange secured between said cap and said shoulder, said stationary piston extending into said cylinder, a hollow piston reciprocable in said cylinder having a retracted position at one end of the cylinder and adapted to telescope over said stationary piston, said stationary piston having sealing means cooperating with the interior of said hollow piston, there being openings communicating with the interior of said hollow piston and said cylinder when said hollow piston is in retracted position, said stationary piston having openings therethrough for the passage of fluid in one direction past said sealing means, said stationary piston having a bore communicating between the interior of said hollow piston and said cap, said cap in turn communicating with the braking system, a retarding valve in said cap to permit ready flow of brake fluid to the braking system and retard reverse flow therefrom, and spring biased valve means for permitting passage of fluid from said cylinder into the reservoir when a predetermined pressure is attained in the cylinder.
